UNITED STATES PATENT OFFICE.

JAMES FILLMORE MATTHEWS, OF EL RENO, OKLAHOMA TERRITORY.

DESIGN FOR A CLOTHES-PIN.

SPECIFICATION forming part of Design No. 33,285, dated October 2, 1900.

Application filed August 21, 1900. Serial No. 27,826. Term of patent 14 years.

To all whom it may concern:

Be it known that I, JAMES FILLMORE MATTHEWS, a citizen of the United States, residing at El Reno, Canadian county, Oklahoma

5 Territory, have invented and produced a new and original Design for Clothes-Pins, of which the following is a specification.

10 My invention relates to a new and original design for clothes-pins, and has for its object to provide a design which is both useful and ornamental.

15 In the accompanying drawings, forming a part of this application, Figure 1 is a face view, and Fig. 2 an edge view, of a clothes-pin, showing my new design.

As shown in said figures, the leading or material feature of my design consists in the representation of a clothes-pin having an isosceles triangle which has straight sides but no 20 straight base and formed with a circular coil or convolution at its apex and a pair of circular coils or convolutions at its lower corners, said coils or convolutions lying wholly within and forming the base of the triangular 25 figure; also, in the intersecting arms, of ap-

proximately right-angle form, which lie within the triangular figure just above the coils or convolutions forming its base, the corners of said arms being rounded.

In detail, 1 designates the isosceles-triangular-shaped figure. 2 designates the straight sides of the same. 3 designates the coil or convolution at the apex of the figure. 4 4 designates the coils at the base and lower corners of said figure. 5 designates the substantially right-angle-shaped intersecting arms within the figure and just above the base coils or convolutions, and 6 designates the rounded corners of said arms.

Having thus described the invention, what I claim as new, and desire to secure by Letters Patent, is—

The design for a clothes-pin herein shown and described.

In testimony whereof I affix my signature in the presence of two witnesses.

JAMES FILLMORE MATTHEWS.
